UNITED STATES PATENT OFFICE

ERNEST S. CARPENTER, OF CLEVELAND HEIGHTS, OHIO, ASSIGNOR TO AUGUSTUS
CARPENTER CORPORATION, OF CLEVELAND, OHIO, A CORPORATION OF OHIO

DESIGN FOR A MOTION PICTURE PROJECTOR

Application filed April 26, 1932. Serial No. 43,611. Term of patent 14 years.

To all whom it may concern:

Be it known that I, ERNEST S. CARPENTER, a citizen of the United States, residing at Cleveland Heights, in the county of Cuyahoga and State of Ohio, have invented a new, original, and ornamental Design for a Motion Picture Projector, of which the following is a specification, reference being had to the accompanying drawings, forming a part thereof.

The drawings are perspectives of my mo-

tion picture projector;—Fig. 1 looking at the right-hand side; Fig. 2 at the left-hand side; Fig. 3 at the front, and Fig. 4 at the rear. Fig. 1 shows the reel-carrying arms in normal extended position, and Fig. 2 in folded position for storage.

I claim:

The ornamental design for a motion picture projector, substantially as shown and described.

ERNEST S. CARPENTER.
